UNITED STATES PATENT OFFICE.

EDWARD TILSTON, OF MANCHESTER, ENGLAND.

DESIGN FOR A SPANNER-HANDLE.

SPECIFICATION forming part of Design No. 24,290, dated May 7, 1895.

Application filed December 18, 1894. Serial No. 532,265. Term of patent 31 years.

To all whom it may concern:

Be it known that I, EDWARD TILSTON, a subject of the Queen of Great Britain, residing at Manchester, England, have invented and produced a new and original Design for a Spanner-Handle, of which the following is a specification, reference being made to the accompanying drawings, in which—

Figure 1 represents a plan view of my new design, and Fig. 2 a section taken on the line xx of Fig. 1.

My design has the particular shape and configuration shown in the said figures and comprises the representation of a handle having

a recess or slot composed of parts a , b , and c , the said part a being enlarged laterally and all of the said parts of the slot having the shape and arrangement shown.

Having thus described my design, what I claim as new, and desire to secure by Design Letters Patent, is—

The design for a spanner handle having the shape and appearance above described and shown in the accompanying drawings.

EDWARD TILSTON.
